UNITED STATES PATENT OFFICE.

MARK H. DAMERELL, OF WORCESTER, MASSACHUSETTS, ASSIGNOR TO WYMAN-GORDON COMPANY, OF WORCESTER, MASSACHUSETTS, A CORPORATION OF MASSACHUSETTS.

SHAFT-STRAIGHTENING MACHINE.

Application filed May 12, 1927. Serial No. 190,910.

This invention relates to a machine for straightening forged crankshafts and other similar articles. In the machine shown in the drawings, the crankshaft is supported 5 on centers on a sliding table and is movable longitudinally with the table to bring any selected portion of the shaft under a ram or striker by which a straightening blow may be delivered.

10 It is the general object of my invention to provide improved devices for moving the table longitudinally and for moving the ram or striker vertically, by which improved devices the machine may be more conveniently 15 operated and by the use of which the pressure of the ram may be easily and accurately controlled to suit varying conditions.

20 My invention further relates to arrangements and combinations of parts which will be hereinafter described and more particularly pointed out in the appended claims.

A preferred form of the invention is shown in the drawings in which

25 Fig. 1 is a front elevation of the machine, with portions of the shaft-supporting heads omitted;

Fig. 2 is a plan view of certain parts of the driving mechanism;

30 Fig. 3 is an end elevation of parts of the machine, looking in the direction of the arrow 3 in Fig. 1;

35 Fig. 4 is a partial sectional front elevation, taken along the line 4—4 in Fig. 3 and showing the mechanism for moving the table longitudinally;

Fig. 5 is a sectional end elevation, taken along the line 5—5 in Fig. 1;

40 Fig. 6 is a front elevation of certain parts, looking in the direction of the arrow 6 of Fig. 5;

Fig. 7 is a side elevation of the piston cylinder, looking in the direction of the arrow 7 in Fig. 6;

45 Fig. 8 is a front elevation of certain controlling mechanism for the oilgear pump;

Fig. 9 is a detail plan view, looking in the direction of the arrow 9 in Fig. 8;

Fig. 10 is a sectional front elevation of the valve for controlling the table feed;

50 Fig. 11 is a sectional plan view, taken along the line 11—11 in Fig. 12;

Fig. 12 is an end elevation of the valve mechanism, looking in the direction of the arrow 12 in Fig. 10;

55 Fig. 13 is a sectional end elevation of the valve mechanism, taken along the line 13—13 in Fig. 11;

Fig. 14 is a partial elevation of the piston valve sleeve;

60 Fig. 15 is a side elevation of the oil motor which actuates the sliding table, looking in the direction of the arrow 15 in Fig. 4;

Fig. 16 is a rear elevation, partly in section, of the oil motor, looking in the direction of the arrow 16 in Figs. 3 and 15;

65 Fig. 17 is a side elevation of the rotor for the oil motor;

Fig. 18 is a side elevation of the upper section of the cam ring for the motor;

70 Fig. 19 is a similar view of the lower section;

Fig. 20 is a partial elevation, looking in the direction of the arrow 20 in Fig. 18;

75 Fig. 21 is a side elevation of one of the rotor vanes; and

Fig. 22 is a plan view, looking in the direction of the arrow 22 in Fig. 21.

Referring particularly to Fig. 1, my improved shaft straightening machine comprises a table 30 slidable in suitable guide-ways on a base 31, and supporting heads 32 and 33 provided with centers 34 and 35 upon which a crankshaft S may be supported and rotated. The center 34 may be fixed or free to rotate and the center 35 may be positively 80 rotated. The centers 34 and 35 are preferably so mounted in the heads 32 and 33 that they are free to yield, both vertically and laterally, during the straightening operation. For a complete disclosure of the construction of the heads 32 and 33, reference is made to my prior application Serial No. 114,844, filed June 9, 1926.

85 A ram 38 is mounted to slide vertically in guide-ways in a bracket or frame member 39 (Figs. 5 and 6) which is firmly secured to the base 31. The ram 38 is provided with a striking member 40 which is detachably secured, so that a striker of suitable form may 90 be selected for use with a particular crank-shaft.

95 The ram 38 is of substantially U-shaped or goose-neck contour, with a lower end portion 41 offset below the supporting bracket 39. The portion 41 extends forward under the table 30 and is provided with a piston 42 having a head 43 and with suitable packing members 44 and 45 above and below said 100 105

head. A projection 46 on the head 43 limits upward movement of the piston by engagement with the under side of a heavy bed plate 47 forming a part of the base 31.

5 *Ram actuating mechanism.*

A cylinder 50 (Fig. 5) is mounted on the under side of the bed plate 47 and is provided with a cylinder head 51 having a stuffing box 52 for the piston 42. Side plates 54, forming part of the base 31, enclose the cylinder 50 and these side plates are firmly secured to the guide-way bracket 39, so that the guide-ways and cylinder form substantially a unitary 15 construction, with the cylinder 50 always in exact parallel alignment with the guide-ways in the bracket 39.

By placing the cylinder 50 in the base of the machine, I greatly improve the appearance of the machine and also avoid the use of 20 a lot of over-head mechanism for actuating the striker above the work. I also provide a machine with a low center of gravity, as the heavy actuating mechanism is below the table 25 and only the upper portion of the ram or striker 38 extends above the table.

The cylinder 50 is provided with upper and lower ports 56 and 57 by which oil or other fluid under pressure may be admitted above 30 or below the piston head 44. This oil under pressure may be taken from any suitable source of supply but in the present machine I preferably connect the ports 56 and 57 with the outlet pipes of an oilgear pump 60 (Fig. 35 2) which may be driven by a belt or chain 61 from a motor 62. The oilgear pump is a commercial apparatus which it is not necessary to describe in detail, beyond stating that the rotor is driven continuously but that the effecting 40 pumping action may be varied as desired from no delivery at all to the full capacity of the machine.

Pump control.

45 The pump is controlled in my improved machine by means of a handle 63 (Figs. 5 and 6) fixed on a shaft 64 having an arm 65 projecting upwardly therefrom and secured thereto. A link 66 (Fig. 5) is pivoted to the upper end 50 of the arm 65 and is provided with a block 67 fixed on a pilot rod 68. The rod 68 slides within a control member 69 having a hook 70 engaging the outer face of the block 67.

When the handle 63 is pulled forward in 55 the direction of the arrow *a* in Fig. 5, the block 67 will pull the pilot rod 68 outward a certain distance, which in turn will cause the control member 69 to move until said member 60 engages the block 67. Such movement of the member 69 will cause the pump 60 to become operative to an extent determined by the movement of the lever 63. Oil will then be pumped through the port 56 to the cylinder 50, depressing the piston 42 and bringing the 65 striker 40 down against the crankshaft which

will be forced downward with the centers 34 and 35 until it engages rigid supports 70 (Fig. 1) against which straightening pressure may be exerted.

As soon as the handle 63 is released, a 70 coil spring 71 (Fig. 6) on the shaft 64 swings the handle rearward in a direction opposite to that of the arrow *a* in Fig. 5 and returns the pump 60 to neutral or inoperative condition.

As the ram approaches extreme lower position, a cam 72 (Fig. 5) mounted on a lug 73 on the side of the ram 38 engages a roll 75 on the lower end of an arm 76 (Fig. 6) secured to one end of the shaft 64. When the cam 72 thus engages the roll 75, the handle 63 will be 80 forced rearward, acting through the pilot rod to bring the pump to neutral position.

When the handle is released by the operator, the spring 71 throws the handle back far enough to reverse the operation of the pump 60, pumping oil into the port 57 and raising the piston 42 until a second cam plate 77 on the ram 38 engages the roll 75 and forces the lever 63 forward to neutral position. The parts thus come to rest with the ram in raised 90 position.

I am thus able to apply carefully graduated pressure to the crankshaft to bend the same to any amount which is indicated as necessary for straightening the same, and as soon as the 95 handle 63 is released, the ram automatically returns to its extreme upper position. If the lever 63 is moved to neutral position at an intermediate point in the travel of the piston, the parts will be maintained under pressure in 100 such position.

Table feed.

I will now describe the mechanism for feeding the table 30 longitudinally and for controlling the rate and direction of feed. The table 30 (Fig. 4) is provided with a nut 80 adapted to travel on a lead screw 81 supported in thrust bearings 82 mounted on the bed plate 47 of the machine frame. The lead screw 81 is provided with a sprocket 83 connected by a sprocket chain 84 to a second sprocket 85 fixed on the end of an oil motor shaft 86.

The shaft 86 is mounted in suitable bearings 115 in a motor casing 87 and is provided with a rotor 88 rotatable within the casing. A cam ring comprising an upper portion 90 and a lower portion 91 is mounted in fixed position within the casing 87 and is held from rotation 120 therein by pins 92.

The cam ring 91 has an inner cylindrical surface 93 concentric with the axis of the motor shaft 86. The cam ring 90 has a similar surface 94 also concentric but of substantially less diameter. At each end of the surface 94 there is provided a beveled cam portion 95 forming a sloping connecting surface between the two concentric surfaces 93 and 94. 125

Supply pipes 96 and 97 are connected with 130

passages 98 within the casing 87, these passages 98 terminating in ports 99 (Fig. 20) through which oil or other liquid under pressure may be introduced to the rotor.

5 The rotor 88 (Figs. 16 and 17) is provided with a plurality of radial recesses or slots 100, adapted to receive vanes 101, slideable radially of said circumferentially spaced recesses. Each vane 101 is provided with pockets 102 to receive the ends of compression springs 103, the opposite ends of which are seated in pockets 104 in the rotor, extending inward from the recesses 100. A vent hole 106 is also provided in each vane to permit free 15 sliding movement thereof without compression of air or liquid within the recesses 100.

The operation of the oil motor is clearly shown in Fig. 15. Assuming that oil under pressure is supplied to the pipe 96, this oil 20 flows through the corresponding passage 98 and port 99 and enters the circumferential space between the rotor 88 and the cam surface 93. As the oil flows along this segmental 25 passage it encounters one of the vanes 101 and exerts a rotating pressure thereon. The rotor then begins to rotate, successively presenting additional vanes in the path of the oil under pressure and retaining the oil between the vanes until the opposite port 99 is 30 reached, at which point the oil escapes through the passage 98 to the pipe 97.

During the remaining portion of the revolution, the rotor 88 and the cam surface 94 are quite closely in contact, so that there is no 35 substantial space left for the exertion of oil pressure. Consequently, the vanes in the lower part of the casing are pushed forward by the oil and the vanes in the upper part of the casing rotate freely until they again reach 40 operative position.

The pump is completely reversible, as it is merely necessary to supply oil through the pipe 97 instead of the pipe 96 to cause the pump to rotate in the opposite direction. 45 The speed of rotation is controlled entirely by the oil pressure or by the rate at which oil is allowed to enter the pump. The oil under pressure provided for operating my improved pump may be derived from any suitable 50 source, such as a compression pipe line, the source of supply forming no part of my present invention.

Motor controlling mechanism.

55 While the source of supply of oil under pressure is immaterial, I have provided special mechanism for conveniently controlling the flow of oil to the motor. For this purpose I have provided a handle 110 (Fig. 1) pivoted at 111 and connected by a link 112 to an arm 113 on the front end of a rock shaft 114.

The shaft 114 (Fig. 3) is suitably supported in bearings 115 in the base 31 and is provided at its rear end with an upwardly extending arm 116 and a downwardly extend-

ing arm 117, both fixed to the shaft 114. The arm 117 is connected by a link 118 (Fig. 4) to an upright lever 119 mounted on a lug 120 projecting from the valve casing 121.

The lever 119 is normally held in upright 70 mid-position by a positioning rod 122 pivoted to the lever at 123 and provided with flanged bushings 124 and 125 slideable in bearings 126 projecting upward from the valve casing 121. The bushings 124 and 125 are 75 loose on the rod 122 and are provided with flanges at each end. The bushing 124 abuts a shoulder on the rod 122 and the bushing 125 abuts a nut on the end of the rod 122. A coil spring 127 engages the inner flanges between 80 the bearing projections 126. Whenever the lever 119 is displaced in either direction, as indicated in the broken lines in Fig. 10, one of the flanged bushings 124 or 125 is caused to slide through its bearing 126 and to compress 85 the spring 127. At the same time, the other bushing remains unmoved in its projection 126, while the rod 122 slides therethrough. As soon as the handle is released, the spring returns the positioning rod 122 to normal position, with the lever 119 in upright or neutral position. 90

A piston valve 130 is connected by a link 131 to the lower end of the lever 119. The valve 130 is provided with piston portions 95 132, 133, 134 and 135 and with recessed portions 136, 137 and 138. A valve sleeve 140 is inserted in the casing 121 and is provided with a series of annular recesses 141, 142, 143, 144, 145, 146 and 147, each extending around 100 the outer surface of the sleeve 140 and connected by a plurality of radial passages 148 to the interior of the sleeve.

An inlet pipe 150 is connected to an axially extending passage 152 (Fig. 10) within the 105 casing 121, which passage is connected by radial passages 153, 154, and 155 with the three middle recesses 143, 144 and 145 of the valve sleeve 140.

An exhaust pipe 151 is connected with an 110 axially extending passage 156 (Fig. 11) which in turn is connected by radial passages 157 and 158 to the end recesses 141 and 147 in the valve sleeve 140. The supply pipes 96 and 97 for the oil motor are connected to the remaining recesses 142 and 146 of the valve 115 sleeve 140.

When the lever 119 is in mid-position, as shown in Fig. 10, the pipes 96 and 97 are not connected to the supply or to the exhaust, and the motor remains stationary. If the lever 119 is moved by the handle 110 to carry the piston valve 130 to its left hand position, as viewed in Fig. 10, oil under pressure is admitted from the pipe 150 through the passages 152 and 155 to the sleeve recess 145 and thence through the valve recess 138 to the valve recess 146 which is connected with the motor supply pipe 96. At the same time, the pipe 97 from the motor will be connected 125 136

through the sleeve recess 142 and the valve recess 136 to the sleeve recess 141 and thence through the passages 157 and 156 (Fig. 11) to the exhaust pipe 151.

5. With the parts positioned as above described, the rotor will move in the direction of the arrow *b*, as indicated in Fig. 15, and will continue to rotate in this direction until the lever 119 is released, when the compression spring 127 will immediately move the handle to mid-position and stop rotation of the rotor 88.

Movement of the lever 119 by the handle 110 in the opposite direction will cause similar rotation of the rotor 88 but in the reverse direction. I am thus able to rotate the lead screw 81 in either direction and for any desired amount of angular movement and I thus move the table 130 to the right or to the 20 left and accurately position the same under the striker 40.

With this full description of the construction and operation of my improved machine, it is believed that the method of using the 25 same and the advantages thereof will be readily apparent. The entire machine is very conveniently controlled by the two handles 63 and 110. The handle 110 controls the oil motor by which the table 30 may be 30 quickly and easily shifted longitudinally to any desired position, and the handle 63 controls the operation of the oilgear pump 60 by which the ram 38 is operated.

In case the operator neglects to stop the oil 35 motor when the table 30 reaches its extreme limit of travel in either direction, I provide stop pins 160 (Fig. 3) adapted to engage the upwardly extending arm 161 of a lever 162 having a depending arm 163 connected to the 40 arm 116 on the control shaft 114. When the arm 161 is engaged by a pin 160 moving in either direction, the piston valve 130 is moved to neutral mid-position.

Having thus described my invention and 45 the advantages thereof, I do not wish to be limited to the detail herein disclosed otherwise than as set forth in the claims, but what I do claim is:—

1. A shaft straightening machine comprising a base, a table slidable thereon, centering heads on said table, a vertically movable striker, guide-ways for said striker fixed to said base at the rear of said table, and actuating means for said striker mounted below 55 said table.

2. A shaft straightening machine comprising a base, a table slidable thereon, centering heads on said table, a vertically movable striker, guide-ways for said striker fixed to 60 said base at the rear of said table, said striker being substantially U-shaped and having a piston on its forwardly projecting lower end, and a cylinder for said piston mounted in said base below said table.

65 3. The combination in a shaft straighten-

ing machine as set forth in claim 2, in which said striker has a forwardly projecting upper end portion with a shaft-engaging element thereon and in which said engaging element is in substantial alignment with the 70 axis of said piston and cylinder.

4. In a shaft straightening machine, a striker having offset forwardly projecting upper and lower end portions and a connecting portion, a shaft-engaging element on 75 said upper end portion, a guide-way in which said connecting portion is slidable and fluid actuated means to apply power to the lower end portion of said striker in substantial alignment with the path of movement of 80 said shaft engaging element.

5. In a shaft straightening machine, a base, means to rotatably support a shaft thereon, a bracket secured to the rear side of said base and having upright guide-ways 85 therein, a striker slidable in said guide-ways and having forwardly projecting upper and lower end portions, a shaft-engaging element on said upper end portion, a piston on said lower end portion, a cylinder for said piston, and means to secure said cylinder in fixed position in said base and parallel to said guide-ways.

6. In a shaft straightening machine, a base, means to rotatably support a shaft 95 thereon, a bracket secured to the rear side of said base and having upright guide-ways therein, a striker slidable in said guide-ways and having forwardly projecting upper and lower end portions, a shaft-engaging element 100 on said upper end portion, a piston on said lower end portion, a cylinder for said piston, and securing means for said cylinder bolted to said bracket and retaining said cylinder in permanent fixed alignment with said guide-ways.

7. A shaft straightening machine having a shaft-supporting table, vertical guide-ways fixed at the rear of said table, a striker slidable in said guideways and having forwardly projecting upper and lower end portions, said striker having a shaft-engaging element on its upper end portion, and actuating means for said striker fixed in position below said table and operative on said forwardly projecting lower end portion to move said striker vertically in said guide-ways.

8. In a shaft straightening machine, a shaft-engaging striker having a limited travel, actuating means therefor including a 110 cylinder and piston, one of said elements being directly secured to said striker, means to supply fluid under pressure to either end of said cylinder, a manually controlled lever for said fluid supply means, and automatic 115 means to force said control lever to neutral mid-position at either limit of the path of travel of said striker.

9. In a shaft straightening machine, a shaft-engaging striker having a limited 120

travel, actuating means therefor including a cylinder and piston, one of said elements being directly secured to said striker, means to supply fluid under pressure to either end 5 of said cylinder, a manually controlled lever for said fluid supply means, a spring effective to move said control lever when released to reverse position, and means to move said lever to neutral position at the upper limit of 10 travel of said striker.

10. In a shaft straightening machine, a shaft-engaging striker having a limited travel, actuating means therefor including a cylinder and piston, one of said elements 15 being directly secured to said striker, means to supply fluid under pressure to either end of said cylinder, a manually controlled lever for said fluid supply means, means to move said lever to neutral position at the lower 20 limit of travel of said striker, a spring effective when said lever is released to move said lever to reverse position, and means to move said lever again to neutral position at the upper limit of travel.

25. 11. In a shaft straightening machine, a shaft-engaging striker having a limited travel, fluid operated actuating means therefor including an oilgear pump, means to rotate said pump continuously, a control handle 30 by which said pump may be caused to exert pressure to move said striker in either direction, and means directly controlled by said striker to render said pump inoperative at each end of the path of travel of said 35 striker.

12. In a shaft straightening machine, a shaft-engaging striker having a limited travel, fluid operated actuating means therefor including an oilgear pump, and manual 40 means to control said pump to move said striker at a desired speed in either direction, and to maintain said striker under pressure at an intermediate position thereof.

13. In a shaft straightening machine, a 45 striker, a shaft-supporting table movable longitudinally beneath said striker, a lead screw to move said table, a reversible fluid motor connected to rotate said lead screw, said motor having a supply of fluid under pressure, and manual means effective to admit 50 said fluid to rotate said motor in either direction and to any desired extent.

14. In a shaft straightening machine, a striker, a shaft-supporting table movable longitudinally beneath said striker, actuating 55 mechanism for said table, a reversible fluid motor connected to drive said actuating mechanism, said motor having a supply of fluid under pressure, and a manually controlled piston valve by which either side of said 60 motor may be caused to receive fluid under pressure, the opposite side of said motor being simultaneously connected to the motor exhaust.

15. The combination in a shaft straightening machine as set forth in claim 14, in which 65 said motor is held from rotation in either direction when said valve is in mid-position.

16. The combination in a shaft straightening machine as set forth in claim 14, in which 70 automatic means is provided to move said valve to neutral mid-position when released after displacement in either direction.

17. The combination in a shaft straightening machine as set forth in claim 14, in which 75 a lever is provided for said valve, a rod connected to said lever, a pair of flanged bushings on said rod, spaced bearings for said bushings, said bushings being slidable axially on 80 said rod and in said bearings, abutments on said rod to limit sliding movement of said bushings thereon, and a compression spring mounted on said rod between said bushings and bearings, said spring being effective to 85 move said lever to mid-position when released.

18. The combination in a shaft straightening machine as set forth in claim 14, in which 90 a valve sleeve is provided for said valve, said sleeve having annular recesses connected respectively to the fluid supply and to the fluid exhaust and also to each inlet of the reversible motor.

19. The combination in a shaft straightening machine as set forth in claim 14, in which 95 said table has limited travel and in which means is provided on said table effective to move said piston valve to neutral position at either limit of travel of said table.

In testimony whereof I have hereunto affixed my signature.

MARK H. DAMERELL.
